UNITED STATES PATENT OFFICE.

JOHN V. B. CARTER, OF DETROIT, MICHIGAN, ASSIGNOR TO THE DETROIT STOVE-WORKS, OF SAME PLACE.

DESIGN FOR A HEATING-STOVE.

Specification forming part of Design No. 6,018, dated August 6, 1872.

Specification describing a Design for a Stove, invented by JOHN V. B. CARTER, of Detroit, in the county of Wayne and State of Michigan.

The nature of my design is fully represented in the accompanying photographic illustration, to which reference is made.

A is the base-plate, and is a rich and heavy molding, ornamented as shown. B is the fire-pot section, ornamented by intaglio lines in alto-relievo, forming, as they interlace, a series of octagons, in the center of each of which is a star on a stipple ground. C is the mica section, with a molding above and below it. There are three arched openings to each panel, with a medallion on the center face of each column. The ground-work above the openings is rayed to represent the interwoven shades of watered silk. D is the magazine-section, its ornamentation being in geometrical lines, in alto-relievo, forming the figures shown. The ground-work of one figure is in raised parallel vertical lines, and in the next in parallel horizontal lines, as shown. E is the cap, molded and ornamented as shown. From the edge of the cap is pendent denticu-

lated frieze-molding, a, which stands away from the magazine-section. The cap is surmounted by a statuette copy of Randolph Rogers' allegorical statue of Michigan, although any other appropriate figure may be substituted for it.

What I claim as my invention, and desire to secure by Letters Patent, is—

1. The design for the base-plate A, as shown.
2. The design for the fire-pot section B, as shown and described.
3. The design for mica section C, as described and shown.
4. The design for the magazine-section D, as shown and described.
5. The design for the cap E, ornamented as shown, and surmounted with a statuette, as described.
6. The design of the pendent denticulated molding a at the edge of the cap, as shown.
7. The design for a heating-stove, as shown.

JOHN V. B. CARTER.
